INDEX SYSTEM

Filed July 20, 1929

FIG. 1.

UNITED STATES PATENT OFFICE

MIRIAM ZION, OF NEW YORK, N. Y.

INDEX SYSTEM

Application filed July 20, 1929. Serial No. 379,622.

My invention relates generally to an index system for the purpose of keeping a historic account of medical cases coming under a doctor's care and the invention has particular reference to a folded history card used in this system and the manner in which the same is lined off to contain spaces for a patient's name and other identification data as well as a complete list of findings, history and diagnosis in the case.

The invention has for its object to provide a main card for a medical case history which is provided with a diagnosis index whereby all cards identifying similar cases are readily available for study and comparison.

I accomplish this and other objects of my invention by means of a card and rulings therefor which is fully described in the following specification and claims and illustratively exemplified in the accompanying drawings, in which Figure 1 is a perspective view of an arrangement of cards in my improved index system showing several of the main history cards placed therein; Figure 2 is an elevational view of the main card in open position and a visiting card in place; and Figure 3 is a transverse sectional view taken through the folded main card and visiting card.

Referring to the drawings, 10 denotes a main or history card which is folded longitudinally thereof along one of two adjacent scored lines 11. The upper left portion has two ruled lines 12 for the name and address of the patient, while the upper right-hand edge is provided with a tab 13 ruled vertically into spaces numbered from 1 to 7, for example. The two scorings 11 on the history card permit the front portion to fold over the rear portion so that only the name and address of the patient is visible, one of the scorings 11 being for the purpose of forming a rest for visiting cards 14, which are attached to the history cards. The history card in its back portion is provided with a hole 15 punched in the upper portion to the right to accommodate a fastener 16.

The numbers in the spaces of the tabs 13 represent a diagnosis index and separate tabs

17 with corresponding numbers are attached one to each of the tabs 13.

The index system of which the history cards are part, comprises a diagnosis index file card 18, see Figure 1, on which is entered the type cases found to be of special interest. An adjustable indicator tab 17 is placed over the number on tab 13 which corresponds to the number 19 found on the diagnosis index card 18. This permits the searcher to readily locate all cases of the same type under one number 19. For example, #1 on the index card 18 representing "Pneumonia" would indicate that all history cards 10 having a tab 17 with #1 on it would relate to specific cases of pneumonia. The back of the history card provides space for the date and treatments given. When the back of the history card 10 is completed, another card called the subsequent visiting card 14 is used. Each card 14 is of a size to fit perfectly inside the folded history card and its upper edge extends just below the spaces for the patient's name and address indicated on the history card. The visiting cards 14 are provided with spaces for the patient's name and address; dates of treatments and findings and each card is further provided with two holes 20 punched in the right side adjacent the corners, both holes being intended for the same purpose. The first hole receives the fastener 16, and the second hole permits the visiting card to be reversed when the first side is completed, the reverse side being the same as the first side. The arrangement described herein enables the doctor at all times to have a complete view of his records by simply swinging the card 14 about the fastener 16.

Having now described my invention what I claim and desire to secure by Letters Patent is:

1. In a card system of the character described, a history card comprising a member folded on itself to provide space at the back portion to accommodate certain data visible above the forward portion, the back portion having a tab subdivided by lines on its upper edge and designated by different characters, and a separate tab to be attached to the first tab and having a character cor-

responding with one of the characters of the first tab.

2. A history card as claimed in claim 1, in which the back portion of the history card is provided with a fastening means, and in combination therewith a subsequent visiting card having two holes adjacent the corners on one end adapted to connect with the history card through the fastening means.

10 3. A card system of the character described comprising an index card ruled for the entry of type cases, and a history card comprising a folded member, the rear portion thereof projecting above the forward portion and at one end the upper edge of the rear portion being provided with a ruled tab with characters corresponding to the characters on the index card, and a separate tab mounted on the first tab and having a 15 character corresponding to the character over which it is mounted, said second tab designating by its character and position the type case noted opposite the same character on the index card.

20 4. A history card, as claimed in claim 3, in which the back portion is provided with a hole punched adjacent the upper right corner, a headed fastener projecting through said hole, and a subsequent visiting card having holes adjacent opposite corners at one 25 end to receive the said fastener and attach the card in either of two positions to the history card.

25 5. A history card of the character described, comprising a sheet of material folded along two adjacent scored lines disposed longitudinally thereof, the rear portion having a hole and a fastener therein, a second card to fit between the folds and provided with 30 holes adjacent the corners at one end to receive the fastener in different positions.

40 In testimony whereof she has affixed her signature.

MIRIAM ZION.
